US00D633917S

(12) **United States Design Patent**
Poling et al.

(10) **Patent No.:** US D633,917 S
(45) **Date of Patent:** ** Mar. 8, 2011

(54) **USER INTERFACE FOR A PORTION OF A DISPLAY SCREEN**

(75) Inventors: **Amy Poling**, San Jose, CA (US); **Daniel Walsh**, San Francisco, CA (US)

(73) Assignee: **Adobe Systems Incorporated**, San Jose, CA (US)

(**) Term: **14 Years**

(21) Appl. No.: **29/350,481**

(22) Filed: **Nov. 17, 2009**

Related U.S. Application Data

(62) Division of application No. 29/318,425, filed on May 20, 2008, now Pat. No. Des. 607,889.

(51) **LOC (9) Cl.** 32-00

(52) **U.S. Cl.** D14/485

(58) **Field of Classification Search** D14/485-495; D18/24-33; D19/6, 52; D20/11; D21/324-333; 715/700-867, 973-977; 345/757, 782, 848, 345/852, 850, 809, 837, 798, 752, 163, 156, 345/537, 474, 836, 419, 649, 656, 659, 426, 345/427, 582, 428, 440, 660, 634, 902, 418, 345/629, 700, 744, 747, 473; 705/10, 5; 709/223

CLAIM

The ornamental design for a user interface for a portion of a display screen, as shown and described.

DESCRIPTION

A portion of the disclosure of this patent document contains material that is subject to copyright protection. The copyright owner has no objection to the facsimile reproduction by anyone of the patent document or the patent disclosure, as it appears in the Patent and Trademark Office patent files or records, but otherwise reserves all copyright rights whatsoever. The following notice applies to the software and data as described below and in the drawing that form a part of this document: Copyright 2008 ADOBE SYSTEMS INCORPORATED. All Rights Reserved.

FIG. 1 is a front view of a user interface for a portion of a display screen, according to a first embodiment of our new design; and,

FIG. 2 is a front view of a user interface for a portion of a display screen, according to a second embodiment of our new design.

The dash dot boundary outline of a display screen and the blank space contained within is not claimed. The broken line showing of a rectangular form and the space within is not claimed.
